US00D742059S

(12) **United States Design Patent**
Gettings et al.

(10) **Patent No.:** US D742,059 S
(45) **Date of Patent:** ** Oct. 27, 2015

(54) **NIGHTLIGHT AND AIR SENSOR**

(71) Applicant: **Leeo, Inc.**, Palo Alto, CA (US)

(72) Inventors: **Adam M. Gettings**, Red Wing, MN (US); **Victoria Slaker**, San Francisco, CA (US); **Edward Licitria**, San Francisco, CA (US)

(73) Assignee: **Leeo, Inc.**, Palo Alto, CA (US)

(**) Term: **14 Years**

(21) Appl. No.: **29/483,648**

(22) Filed: **Feb. 28, 2014**

(51) **LOC (10) Cl.** 26-99

(52) **U.S. Cl.**

USPC **D26/120**; D26/123; D26/124

(58) **Field of Classification Search**

(57) **CLAIM**

The ornamental design for a nightlight and air sensor, as shown and described.

DESCRIPTION

FIG. 1 is a front side perspective view of a nightlight and air sensor;

FIG. 2 is a bottom view thereof;

FIG. 3 is a left side elevation view thereof;

FIG. 4 is a rear elevation view thereof;

FIG. 5 is a front bottom perspective view thereof;

FIG. 6 is a right side elevation view thereof;

FIG. 7 is a front elevation view thereof;

FIG. 8 is a top elevation view thereof;

FIG. 9 is a rear bottom perspective view thereof;

FIG. 10 is a rear top perspective view thereof; and,

FIG. 11 is a rear bottom perspective view thereof.

All features illustrated in phantom line are expressly disclaimed and form no part of the claimed.

1 Claim, 11 Drawing Sheets
